UNITED STATES PATENT OFFICE

171,285

ROTATABLE JEWELRY DISPLAY RACK

Stephen Hans Loeb, Brentwood, Mo., assignor to
Hugo Herzberg Company, St. Louis, Mo., a cor-
poration of Missouri

Application September 23, 1953, Serial No. 26,925

Term of patent 14 years

(Cl. D80—9)

To all whom it may concern:

Be it known that I, Stephen Hans Loeb, a citizen of the United States, residing in the city of Brentwood, county of St. Louis, State of Missouri, have invented a new, original, and ornamental Design for a Rotatable Jewelry Display Rack, of which the following is a specification, reference being made to the accompanying drawing, forming a part thereof, in which

The figure is a perspective view of a rotatable jewelry display rack embodying my new design.

I claim:

The ornamental design for a rotatable jewelry display rack, substantially as shown.

STEPHEN HANS LOEB.
